UNITED STATES PATENT OFFICE.

ALBERT V. MARSIK, OF NEW YORK, N. Y.

AUTO HORN.

Application filed October 1, 1924. Serial No. 741,019.

To all whom it may concern:

Be it known that I, ALBERT V. MARSIK, a citizen of the United States, and a resident of the city of New York, Jackson Heights, 5 borough of Queens, in the county of Queens and State of New York, have invented a new and Improved Auto Horn, of which the following is a full, clear, and exact description.

10 This invention relates to horns and more particularly to a mechanically operated horn which is especially adapted for use on automobiles or the like, an object of the invention being to provide a horn which is not liable to get out of order, which can be easily operated and which will give the desired sound.

15 The great majority of horns of this type in general use are electrically operated, and it frequently happens through short circuiting and the like the horn becomes useless. This is a serious matter to a driver of an automobile, and it is the purpose of my invention to provide a horn which will be entirely mechanical, which can be manufactured and sold at a reasonably low price, and which will be most efficient in the performance of its functions.

20 With these and other objects in view, the invention consists in certain novel features of construction and combinations and arrangements of parts which will be more fully hereinafter described and pointed out in the claims.

25 In the accompanying drawings—

Figure 1 is a view partly in longitudinal section and partly in elevation illustrating my improved form;

30 Figure 2 is a view in section on the staggered line 2—2 of Figure 1;

Figure 3 is a view in transverse section on the line 3—3 of Figure 1;

Figure 4 is a face view of the diaphragm 4.

35 1 represents a relatively heavy plate which is circular in form and somewhat cupped, and to the outer edge of this plate a second plate 2 is secured and supports an amplifier 3. This amplifier is secured in a central opening in plate 2 and the plates 1 and 2 constitute a circular chamber in which a diaphragm 4 is secured between the edges of the plates.

40 Plate 1 has a central bearing 5 for a short shaft 6 on which a circular head 7 is fixed and located within the chamber formed between plates 1 and 2. This head has an an-

nular series of serrations 8 each adapted to engage studs 9 fixed to the diaphragm so that when the head is revolved it will cause the diaphragm to vibrate and sounds to be emitted through the amplifier 3. My invention resides more specifically in mechanism for operating the shaft 6 and head 7 thereon, which mechanism will now be described in detail.

45 A frame 10 is fixed to plate 1 and supports three parallel shafts 11, 12 and 13, respectively. On the shaft 11 a relatively large bevel gear wheel 29 is fixed and this gear wheel 29 meshes with a bevel pinion 13 on shaft 6 so as to impart rotary motion to the head 7 when the bevel gear wheel 29 is turned. This gear wheel 29 is made relatively heavy so that it has somewhat the function of a fly wheel to utilize the 50 momentum which may be imparted thereto.

55 A removable casing 14 is secured to the frame 10 and is provided with a longitudinal slot 16 through which a handle 17 projects. The handle 17 is pivotally supported 55 upon a screw or other suitable pivot 18 connected to frame 10, and is formed at its inner end with an integral segmental gear 19 which meshes with a pinion 20 fixed to the shaft 12.

60 On this shaft 12 a convolute spring 21 is wound and is fixed at one end to this shaft and at its other end to the shaft 13. A gear wheel 22 is fixed to shaft 12 and meshes with a pinion 23 on shaft 13. This shaft 13 also 65 carries a gear wheel 24 which meshes with a gear wheel 25 loose on shaft 11. A second gear wheel 26 also loose on shaft 11 meshes directly with the gear wheel 22. A ratchet wheel 27 is fixed to the shaft 10 between the 70 gear wheels 25 and 26, and said gear wheels 25 and 26 carry spring pressed pawls 28 which engage the ratchet wheel 27. It will be noted that the pawls 28 of the respective gear wheels 25 and 26 are oppositely disposed, it being desirable always to turn the shaft 11 in the same direction regardless of which gear wheel 25 or 26 imparts motion thereto.

75 The operation is as follows:

80 When the handle 17 is moved rearwardly the segment 19 transmits motion to the pinion 20 and shaft 12 to wind the spring 21 thereon. At the same time the gear wheel 22 transmits motion through the pinion 23, shaft 13 and gear wheel 24 to the gear wheel 25. As this gear wheel 25 is turned its pawl

28 will engage the ratchet wheel 27 and impart motion to the shaft 11 and the large bevel gear wheel 29, and the latter will turn the pinion 14 and head 7 to sound the horn. 5 When the handle is released the spring 21 will not only return the handle to its forward position but by reason of the fact that it directly engages the gear wheel 26 it will impart motion to the ratchet wheel 27 and 10 shaft 11 to continue the turning movement of the gear wheel 12 and the head 7 in the same direction as above described. In other words, the backward and forward movement of the handle due to the fact that the spring 15 21 is wound in one direction and imparts motion in the other direction will compel the gear wheel 29 to turn in the same direction on both movements of the handle.

While I refer to the spring 21 as being 20 fixed to the shaft 12 as a preferable arrangement, I bend the end of the spring so that it is square in form and fits over a square portion of the shaft, as clearly shown in Figure 2. I would also call attention to the 25 fact that the studs 9, 9 are not in exact alignment so that their engagement with the serrations of the head 7 is alternate rather than simultaneous.

Various slight changes and alterations 30 might be made in the general form of the parts described without departing from my invention, and hence I do not limit myself to the precise details set forth but consider myself at liberty to make such slight 35 changes and alterations as fairly fall within the spirit and scope of the appended claims.

I claim:

1. A mechanically operated horn, comprising a diaphragm casing, an amplifier communicating therewith, a rotary head in 40 the diaphragm casing, having a serrated edge, a stud on the diaphragm engaging the serrated edge of the head, a pinion fixed to turn with the head, a relatively large gear meshing with the pinion, a pivotally mounted lever, a gear train operatively connecting the lever with the said gear wheel, a spring wound by the movement of the lever in one direction, and a gear train operated by the spring as the latter unwinds 45 to impart a rotary motion to said gear wheel.

2. A mechanically operated horn, comprising a diaphragm casing, an amplifier communicating therewith, a rotary head in 50 the diaphragm casing, having a serrated edge, a stud on the diaphragm engaging the serrated edge of the head, a pinion fixed to turn with the head, a relatively large gear meshing with the pinion, a shaft to which 55 said gear wheel is connected, a pair of gears close on the said shaft, pawls carried by said last-mentioned gears and engaged by the pawls, a pivoted lever, a segment fixed to the lever, a second shaft, a pinion on the 60 second shaft engaged by the segment, a spring on the second shaft, a gear train connecting the second shaft with one of the pawl carrying gear wheels, and a gear wheel 65 fixed to the second mentioned shaft and meshing directly with the other of said 70 pawl carrying gear wheels.

ALBERT V. MARSIK.
